CLAIM

The ornamental design for an insulated belt carrier for beverage cans, substantially as shown and described.

DESCRIPTION

FIG. 1 is a front elevational view of an insulated belt carrier for beverage cans showing my new design;
FIG. 2 is a rear elevational view thereof;
FIG. 3 is a top plan view thereof;
FIG. 4 is a bottom plan view thereof;
FIG. 5 is a right side elevational view thereof;
FIG. 6 is a left side elevational view thereof;
FIG. 7 is a front elevational view of a modified form of the insulated belt carrier for beverage cans shown in FIG. 1;
FIG. 8 is a rear elevational view thereof;
FIG. 9 is a top plan view thereof;
FIG. 10 is a bottom plan view thereof;
FIG. 11 is a right side elevational view thereof; and
FIG. 12 is a left side elevational view thereof.
